US0D1018886S

(12) **United States Design Patent** (10) **Patent No.:** **US D1,018,886 S**
(45) **Date of Patent:** **** Mar. 19, 2024**

(54) **DUAL HEAD PERCUSSIVE MASSAGER
TOOL WITH ROUND TIPS**

4,088,128 A 5/1978 Mabuchi
4,513,737 A 4/1985 Mabuchi
4,549,535 A 10/1985 Wing

(71) Applicant: **PlayMakar Inc.**, Fort Worth, TX (US)

(Continued)

(72) Inventors: **Michael J. Williams**, Colleyville, TX (US); **Federico G. Vierheller**, Fort Worth, TX (US)

FOREIGN PATENT DOCUMENTS

CH 388531 A 2/1965
CN 2694966 Y 4/2005

(Continued)

(73) Assignee: **PlayMakar, Inc.**, Fort Worth, TX (US)

(**) Term: **15 Years**

(21) Appl. No.: **29/876,936**

(22) Filed: **May 31, 2023**

(52) **U.S. Cl.**

CLAIM

USPC **D24/215**

The ornamental design for a dual head percussive massager tool with round tips, as shown and described.

(58) **Field of Classification Search**

DESCRIPTION

USPC D24/200, 209, 211, 212, 213, 214, 215;
D7/393; D8/300, 307, 310, 378;
D9/435, 439
CPC A61H 2201/1685; A61H 2201/0165; A61H
23/006; A61H 2201/0119; A61H
2201/1692

FIG. 1 is a perspective view of a dual head percussive massager tool with round tips;

See application file for complete search history.

FIG. 2 is a top view of the dual head percussive massager tool with round tips;

(56) **References Cited**

FIG. 3 is a bottom view of the dual head percussive massager tool with round tips;

U.S. PATENT DOCUMENTS

FIG. 4 is a front view of the dual head percussive massager tool with round tips;

859,424 A 7/1907 Aschburner
890,822 A 6/1908 Tourtel
1,368,782 A 2/1921 Beach
2,122,556 A 7/1938 Buffalow
2,156,839 A 5/1939 Buffalow

FIG. 5 is a back view of the dual head percussive massager tool with round tips;

FIG. 6 is a left view of the dual head percussive massager tool with round tips; and,

FIG. 7 is a right view of the dual head percussive massager tool with round tips.
